UNITED STATES PATENT OFFICE.

HENRY PEASE, OF BROCKPORT, NEW YORK.

IMPROVEMENT IN ROTARY PUMPS.

Specification forming part of Letters Patent No. 38,058, dated March 31, 1863.

To all whom it may concern:

Be it known that I, HENRY PEASE, of Brockport, in the county of Monroe, in the State of New York, have made a new and useful Improvement in Rotary Pumps; and I do hereby declare that the following is a full, clear, and exact description thereof, reference being had to the accompanying drawings, making a part of this specification, in which—

Figure 1 is a side view of my improved pump. Fig. 2 is a longitudinal section of the same. Fig. 3 is an end view of the pump with the cap removed so as to show the cylinder, pistons, butments, and wings. Fig. 4 is a view of two pistons (end view) and one sleeve. Fig. 5 is an end view of two pistons with the sleeve removed so as to show the stems of the pistons. Fig. 6 is a view of one sleeve detached. Fig. 7 is an end view of the same. Fig. 8 is an (outside) end view of the pump-cap detached, and is drawn to a smaller scale. Fig. 9 is an end view of one stuffing-box, and drawn to the scale as Figs. 8 and 10. Fig. 10 is an end view showing the standard-box E, and pulley F and frame B. Fig. 11 is a side view of my improved stuffing-box.

Similar letters of reference indicate corresponding parts in the several figures.

To enable those skilled in the art to fully understand and construct my invention, I will proceed to describe it.

A is the shell or body of the pump, and is bolted firmly to the frame B with the bolts 27, as shown at Fig 1.

K represents the movable cap or head, which is bolted firmly to the flange X of the shell A with screw-bolts 20. The packing v should be of the proper thickness, so as to allow the portion of the cap K that projects inside the shell A, as at 32, Fig. 2, to bear lightly against the pistons C and that portion of the cylinder D, as shown in Figs. 2 and 3. The cap or head 29 and shell A are cast all in one piece, as shown at Fig. 2. a a are arches made in the proper form to support the stuffing-boxes b b and form the chamber 17 and cavity i. These arches a a are attached firmly to the cap of the pump by means of the screw-thread k k, the male thread being cut or formed on the base, or that portion of the arch a marked 31, and the female thread formed in the cap K and marked 33, as shown at Fig. 2. The stuffing-boxes b b are of a tubular form, (see Fig.

11,) bored to fit the cylinder-shaft H, and turned on the outside of the proper size to enter the cavity i, and terminate at the outer end in the form of a nut, (see Fig. 9,) and held in the proper place by the screw-thread h. This improved stuffing-box b is also provided with a waste-chamber, n. (See Fig. 2.). This chamber n is provided with a number of small holes, f, the object of which is to waste any or all the water that may leak past the stuffing at i and into the groove or chamber n, thereby preventing any water reaching that portion of the stuffing-box b indicated by the dotted line 13, (see Fig. 2,) which may be oiled at any time when in operation, (which could not be done when the stuffing is employed at the outer end of the bearing, as in the common mode, as the pressure of the water in the pump, when in operation, is generally too great to admit of it,) and so form a bearing more durable than has been obtained in any other manner heretofore known.

Another object of my improved stuffing-box b may be explained as follows: As the shaft H wears down in the stuffing-boxes b, they (the boxes) may be turned a little, as the case may require, bringing a new portion of it (box b) under the shaft H, thereby bringing the internal working parts of the pump up to the original position without the expense of new boxes. The water-chamber 17 (see Fig. 2) is supplied with water from the inside of the pump by means of the small holes 21 (in the upper part of the main water-way) through the cap 29 and cap K. The object of this water-chamber 17 is to keep a constant pressure of water around that portion of the shaft H that passes through the water-chamber 17, for the purpose of excluding all air that might otherwise be drawn in through the stuffing at i.

D is the cylinder, made in the usual form, and is that portion that drives the pistons C which work in slots 30, (see Fig. 3,) and runs in bearings or stuffing-boxes b b and standard-box E.

C C are two common rotary-pump pistons, provided with stems e e in the usual form. (See Fig. 5.) These stems e e are hollow, as shown at Fig. 2, and contain a coil-spring, W, the object of which is to keep the pistons C C C C snug out to the shell A, butment, and wings 28 and 29.

j is a small rod to keep the spring *W* from kinking or bending.

The piston stems *e e*, as shown at Fig. 5, are very liable to wear out in a very short time when in constant use, and will wear something similar to that indicated by the dotted lines 35 35. The consequence is the piston and stems have to be replaced with new ones every few days, which is attended with delay and expense, or, as in many cases, the pump is condemned as a failure. Now, to obviate the above-named difficulties and failures in the durability of the stems *e e*, I have made an improvement, which consists in forming a tube or sleeve, *s*, (see Figs. 6 and 7,) of the proper length and bore to receive the stems *e e*, as shown at Fig. 4, in such a manner as to protect the stems *e e* almost entirely from any wear. The sleeves *s* may be replaced with new ones for a trifling expense. The common way of driving rotary pumps or applying the power is by belting or gear. If belting is used, the pulley is fastened directly on firmly to the pump-shaft *H*. If gear is used, it is put on in the same manner, and the result is that in a short time the shaft *H* (if a belt is used) is pulled or worn out of line, and thereby the internal parts of the pump are deranged. The difficulty is not generally known, and in many instances the pump is consigned to the old-iron heap in a few weeks, and when gearing has been used I have known them to fail in a few hours; but with my improved mode of hanging the driving-pulleys (or gear) of rotary pumps the above-named difficulties are all avoided.

My improvement consists in the standard-box *E* with an arm, (hollow,) 2. The arm 2 (see Fig. 2) is of the proper length to form a bearing for the pulley or gear *F*, independent of the shaft *H*. The arm 2 is bored of the proper size to form a box or bearing for the shaft *H*, as shown at 36, Fig. 2. The pulley *F* is provided with a clutch, 25, cast firmly to the hub *g*, to match the clutch 6, fastened to the shaft *H* with a screw-bolt, *v*, and of a proper

distance from the clutch 25 to allow the pulley *F* to revolve freely upon the arm 2, in such a manner as not to drive the pump when it is desired not to run. 37 is an oil-hole for supplying the arm 2 and hub *g* with oil. Now, it is obvious that if the standard-box *E* is bolted firmly to the cast-iron frame *B* with the bolts 28 28 (see Fig. 10) the belt or gear that may be used to drive the pump can have no bad effect, so as draw or force the shaft *H* out of its proper place.

Operation: Motion being given to pulley *F* in the direction of the arrow, the water is drawn into the pump at 19, (which causes the check-valve *y* to rise,) and is discharged at 18. The course that the water takes in passing through the pump is fully shown by the four arrows at Fig. 3. The manner of the general working of the pistons of this pump are so common that I will not enter into a useless description further, but will simply state that the pulley *F* is worked in and out of gear by the lever 8, attached to the fork 9, which fork works in a proper groove, *t*, in the hub of the pulley *F*. *P*, small bolt or pin to connect lever 8 and fork 9.

After having thus described my invention, what I wish to secure by Letters Patent, is—

1. The sleeve *s*, in combination with the piston-stem *e*, substantially as described, for the purpose set forth.
2. The adjustable stuffing-box *b* with the perforated waste-chamber *n*, substantially as and for the purpose set forth.
3. The combination of the bearing-arm 2, pulley *F*, and clutch-couplings 25 and 6, substantially as and for the purpose set forth.
4. The combination of the support *a*, water-chamber 17, stuffing-nut *b*, and waste-chamber *n*, substantially as and for the purpose set forth.

HENRY PEASE.
